UNITED STATES PATENT OFFICE

99,560

DESIGN FOR A DISPLAY STAND FOR FOOD OR SIMILAR ARTICLE

Emil Greuter, Zurich, Switzerland

Application July 3, 1935, Serial No. 57,515
In Belgium April 23, 1935

Term of patent 7 years

To all whom it may concern:

Be it known that I, Emil Greuter, a citizen of the Republic of Switzerland, residing at Zurich, Switzerland, have invented a new, original, and ornamental Design for a Display Stand for Food or Similar Article, of which the following is a specification, reference being had to the accompanying drawing, forming part thereof.

The figure is a perspective view of the display stand showing my new design.

I claim:

The ornamental design for a display stand for food or similar article, as shown.

EMIL GREUTER.
